UNITED STATES PATENT OFFICE.

HERBERT A. PHILLIPS AND JOHN G. STAMM, OF CLEVELAND, OHIO.

DESIGN FOR A FLAG, BANNER, PENNANT, OR SIMILAR ARTICLE.

52,179.

Specification for Design.

Patented July 16, 1918.

Application filed December 3, 1917. Serial No. 205,271. Term of patent 3½ years.

To all whom it may concern:

Be it known that we, HERBERT A. PHILLIPS and JOHN G. STAMM, both citizens of the United States, residing at Cleveland, in the county of Cuyahoga and State of Ohio, have invented a new, original, and ornamental Design for a Flag, Banner, Pennant, or Similar Article, of which the following is a specification, reference being had to the accompanying drawing, forming part thereof.

The figure is a plan view of a flag or banner, showing our new design.

We claim:

The ornamental design for a flag, banner, pennant, or similar article, as shown.

HERBERT A. PHILLIPS.
JOHN G. STAMM.
